UNITED STATES PATENT OFFICE.

MINNIE GILMORE, OF GARDEN VALLEY, CALIFORNIA.

VENTILATED LUNCH-BUCKET.

SPECIFICATION forming part of Letters Patent No. 634,132, dated October 3, 1899.

Application filed May 17, 1898. Serial No. 717,121. (No model.)

To all whom it may concern:

Be it known that I, MINNIE GILMORE, a citizen of the United States, residing at Garden Valley, county of Eldorado, State of California, have invented an Improvement in Vented Lunch-Buckets; and I hereby declare the following to be a full, clear, and exact description of the same.

My invention relates to an improvement in buckets of that class which are designed for carrying lunches for workmen and other people.

It consists, essentially, in the means for ventilating the bucket so as to prevent the disagreeable mixing of the odors of different kinds of food which may be carried in the different compartments of the bucket.

Referring to the accompanying drawing, the figure is a vertical section through the bucket.

This bucket consists of as many compartments A B C as may be desired, and these compartments are of substantially uniform diameter and are fitted to set one within the other, with suitable bearing-flanges to retain the parts in position. The cover D fits the upper compartment and has lugs E upon the sides with slots, and the bail F is hinged to the lower compartment, extending up along side the others, so that it can spring into the notches or slots in the lugs and be kept in place, the whole weight being thus supported by the bottom compartment. This bottom compartment is intended to contain coffee or tea, and the next compartment above may contain any article of food, such as meats, which are placed therein. The bottom of this second compartment B is made close, and the side flange is also made tight up to the rim or fillet, which rests upon the top of the compartment A, thus forming a closed or tight portion of the bottom of the compartment B, which will prevent the steam and odors from anything contained in the lower compartment from rising into that above, and thus permeating it. The compartment C fits upon the compartment B with the same rim or fillet and in the same manner in other compartments. These compartments B C and the cover may be one or all of them perforated with small holes G, as shown, to allow the escape of any steam or fumes arising

from the material in either or any of the compartments if the food has been placed in the compartments while warm, and generally 55 these openings serve to ventilate the compartment and to prevent the disagreeable effect arising from cooked food being kept in a tight compartment for a considerable length of time. In some cases the bottoms of some 60 of the intervening compartments may also be perforated, if not objectionable; but if there is any danger of the different kinds of foods and the different compartments becoming tainted with odors from the others it will 65 be preferable to make the bottoms tight, as described for the bottom between the lowest and second compartment, and ventilation then takes place through the sides of the compartments without any communication between them. The top or cover may also be perforated, so that the upper compartment 70 will have the benefit of side and top ventilation.

The usual projection I may be attached to 75 the top of the cover and adapted to receive the cup J for drinking purposes.

Having thus described my invention, what I claim as new, and desire to secure by Letters Patent, is—

1. A lunch-bucket consisting of superposed compartments of substantially uniform diameter and provided, at points above their bottoms, with flanges or fillets whereby the compartments are supported one above the 85 other to present continuous and substantially unbroken sides throughout the height of the bucket, said compartments having the portions above the flanges or fillets perforated and the portions below the flanges or fillets 90 imperforate and fitting within the open end of a lower compartment, a cover having lugs and a bail secured to the lower compartment and having its side members extending along the other compartments and adapted to spring 95 into engagement with and be held by said lugs.

2. A lunch-bucket consisting of superposed compartments of substantially uniform diameter and provided with flanges or fillets at 100 points above their bottoms whereby the compartments are superposed and substantially continuous and unbroken sides are formed for the full height of the bucket, said com-

partments having a perforate portion above the flange or fillet and an imperforate portion below said flange and adapted to fit closely within the open top of a lower compartment, 5 a cover for the uppermost compartment, having a central projection and having the portion outside of the circumference thereof perforated, said cover having lugs on its outer

edge adapted to be engaged by the bail to secure the series of compartments.

In witness whereof I have hereunto set my hand.

MINNIE GILMORE.
